UNITED STATES PATENT OFFICE.

CHARLES F. DILL, OF GLENARM, ILLINOIS.

TATTING-SHUTTLE.

1,173,102.

Specification of Letters Patent. Patented Feb. 22, 1916.

Application filed September 14, 1914. Serial No. 861,732.

To all whom it may concern:

Be it known that I, CHARLES F. DILL, a citizen of the United States, residing at Glenarm, in the county of Sangamon and State of Illinois, have invented new and useful Improvements in Tatting-Shuttles, of which the following is a specification.

My invention relates to improvements in tatting shuttles, and has for its object the provision of a simple and inexpensive device of that character upon which the thread may be easily and speedily wound, and which will be provided with means for picking out knots which are known to frequently occur in the process of making lace by this method.

With the above and other objects in view, my invention consists of the new and useful construction and arrangement of parts, which will be hereinafter fully described, illustrated in the attached drawings, and pointed out specifically in the appended claim.

In the accompanying drawings, wherein the preferred embodiment of my invention is illustrated, like reference characters refer to like or corresponding parts, throughout the several views.

Figure 1 is a side elevation of the tatting shuttle constructed to embody the improvements of my invention. Fig. 2 is a plan view of my tatting shuttle. Fig. 3 is a perspective view of the thread reel. Fig. 4 is another adaptation of the thread reel. Fig. 5 is a sectional view of a shuttle constructed to embody my invention, and provided with the thread reel shown in Fig. 4.

Referring now more particularly to the drawings, numeral 1 designates the main body of the tatting shuttle, which comprises two side walls tapered from the center toward the pointed ends. The ends 2 and 2' of the shuttle are preferably solid, end 2' being provided with a pin 3 securely fixed therein.

Numeral 4 designates the thread reel in general, it comprising a pair of parallel disks and a spool formed therebetween and integral therewith. Bosses such as 8 are provided on the inner walls of the shuttle, which bosses are adapted to enter depressions 9 on the thread reel, whereby to center the reel and to keep it in place.

It will be understood that the shuttle of my invention may be made of any material, but it is preferred to use celluloid, or simi-

lar resilient material. The side walls of the shuttle may then be sprung slightly outward to admit the reel and the bosses thereon, the walls readily returning to their normal position when the bosses 8 have entered the corresponding depressions in the reel.

In the other embodiment of my shuttle a projecting shaft on boss 7 extends out from each side of the reel, which boss is adapted to fit into a hole or depression on the inner walls of the shuttle, thus centering the reel in the shuttle. I provide simple and novel means for winding the thread on the thread reel. Numeral 11 illustrates a cut-away portion in each of the walls of the shuttle on one of the edges thereof, the cut-away portion extending down slightly lower than the outer periphery of the disks 5 of the reel. It will be readily seen that with a very natural movement of the thumb, while the shuttle is held in the same hand, the thread entered in hole 10 of the spool 6 may be wound about the spool, by revolving disks 5 with the thumb. To facilitate this movement of the reel, the edges of disks 5 may be milled. It will also be seen that since my thread reel is removable, the same may also be filled by winding the thread thereon after withdrawing the reel from the shuttle, the side walls being sprung slightly by the operator to permit the removal and replacing of the reel. The pin 3 provides a necessary implement to pick out knots as they occur in the thread during the process of making lace, the pin being securely fastened in one of the points of the shuttle by any suitable means.

From the foregoing description, it will be readily seen that my invention provides a simple and inexpensive tatting shuttle upon which the thread may be readily wound, and in which is incorporated a novel means for picking out knots in the thread.

While I have herein described and illustrated the preferred embodiment of my invention, I do not wish to be restricted thereto, except for such limitations as the claim may import, as it is obvious that the details of construction may be varied in many ways.

Having thus described my invention, what I claim is:—

In a tatting shuttle, a main body having side walls tapering together at each end and united adjacent the ends, a thread reel

provided with a centering depression on the outer faces of said reel, said main body having inwardly extending pivoting lugs on the inner faces of the side walls positioned 5 to enter the centering depressions on the reel, and each of said side walls provided with a cut-away portion in one of the edges

thereof whereby the thumb of an operator may revolve the reel in said body, substantially as described.

CHARLES F. DILL.
